UNITED STATES PATENT OFFICE

JOSEPH KSOLL, OF BRESLAU, GERMANY

AEROPLANE SUPPORTING SURFACE

Application filed January 6, 1930, Serial No. 418,831, and in Germany January 7, 1929.

Patent application Serial No. 337,422 dated February 4, 1929, describes an aeroplane carrying surface with transversely directed nozzle-shaped gaps extending inclined towards the rear from the underside towards the upper side and unite above the head of the rear supporting surface in a common outlet gap. This supporting surface is remarkable for the fact that with a small angle of adjustment the values of the raising force and resistance are approximately similar to the corresponding values of an ordinary supporting surface.

This invention relates to an arrangement, enabling the closing of the gaps, in order to transform the supporting surface into an ordinary plane, and it consists in that a device similar to a Venetian-blind covering the inlet opening of the nozzle-shaped gap and arranged on the under side of the supporting surface is used for closing each of the nozzle-shaped gaps.

The employment of a single flap or single plane is known for closing the opening of a nozzle-shaped gap, the dimensions of such flaps corresponding in the longitudinal direction of the supporting surface with those of the gap inlet. These known closing devices are however, if they move within the section of the supporting plane, difficult to operate by hand, as the pressure, acting on the flap or surface which has to be overcome when moving the flap into the closing position, is very great, whereas, if the flap or plane lies in the open position entirely or partly outside the ordinary plane section, the air flow on the lower side of the aeroplane supporting surface and therefore the effect of the nozzle-shaped gap is considerably affected.

Consequently, according to the invention, a Venetian blind surface is provided, instead of the usual single flap or plane, and composed of a plurality of small flaps or planes, movable within the ordinary plane section.

An embodiment of the invention is illustrated by way of example in the only figure of the accompanying drawing in which:

a, b and *c* are the parts of the supporting surface, separated by nozzle-shaped gaps *d* and *e*, the part *c*, known as the flap, being

adapted to oscillate around the axle *f* into the position shown in dash lines. The two nozzle-shaped gaps *d* and *e* end in a common gap *g*, which only extends to the rear to above the front part of the flap *c* and which is still further narrowed from the inlet point *h* towards the outlet *i*. The rear portion of the supporting surface part *a* may form a separate adjusting surface *a'*, rotatable around the pivot *a''* and connected with the flap *c* by means of a link *k* so that, at horizontal flight (travelling flight) the gap mouth *i* is more or less closed and on lowering the flap the gap mouth is widened.

On the under side of the aeroplane supporting surface Venetian blind surfaces *l* are provided as gap closures, by means of which the ends of the nozzle-shaped gaps *d* and *e* can be covered. These Venetian blind surfaces are preferably connected with the flap *c* by a lever mechanism, not shown, so that on the lowering of the flap the Venetian blind surfaces suddenly open, thereby very considerably increasing the lifting force and that they again close when the flap is being moved into the horizontal position, whereby the lifting force is reduced again to that of an ordinary supporting surface. The Venetian blind surfaces also present the advantage, that the air eddy current occurring on the lower side of the supporting surface cannot enter as a whole into the nozzle-shaped gaps, but is divided into sub-eddies and thereby weakened.

I claim:

An aeroplane supporting surface, comprising in combination a rear flap, a main supporting surface having transverse nozzle-shaped gaps leading to in front of and behind the centre of the supporting surface from the under side inclined towards the rear to the upper side and uniting above the head of the rear flap in a common further narrowed outlet gap, and a Venetian blind surface composed of movable small flaps arranged within the section of the supporting surface adapted to close the inlet ends of said gaps.

In testimony whereof I affix my signature.
JOSEPH KSOLL.
